COMBINED DRAWER FRONT, PULL AND LABEL HOLDER

Peter J. Protzmann, Grand Rapids, Mich., assignor to Herman Miller Inc., Zeeland, Mich., a corporation of Michigan

Continuation-in-part of design application Ser. No.
13,401, Sept. 5, 1968. This application May 12,
1969, Ser. No. 17,114

Term of patent 14 years

Int. Cl. D6—00; D8—03
U.S. Cl. D33—1

FIG. 1.

FIG. 2.

FIG. 3.

FIG. 4.

FIG. 5.

FIG. 6.

FIG. 7.

FIG. 8.

FIG. 1 is a perspective view of a combined drawer front, pull and label holder showing my new design;

FIG. 2 is a front elevational view;

FIG. 3 is a left side elevational view;

FIG. 4 is a top plan view;

FIG. 5 is a perspective view of a combined drawer front, pull and label holder showing another form of my new design;

FIG. 6 is a front elevational view thereof;

FIG. 7 is a left side elevational view thereof; and

FIG. 8 is a top plan view thereof.

I claim:

The ornamental design for a combined drawer front, pull and label holder, as shown.
